(57) **CLAIM**

The ornamental design for a handbag, as shown and described.

DESCRIPTION

FIG. 1 is a front left perspective view of a handbag showing my new design;

FIG. 2 is a front elevation view thereof;

FIG. 3 is a rear elevation view thereof;

FIG. 4 is a left side view thereof;

FIG. 5 is a right side view thereof;

FIG. 6 is a top plan view thereof;

FIG. 7 is a top plan view in an alternate configuration, where the front and rear sides are spread open toward the front and rear, respectively; and,

FIG. 8 is a bottom view of the configuration shown in FIG. 6.

The broken lines depict stitching and are included in the claimed design.
